DES. 2169

W. T. Remington of Bridgeport Conn.

Letters Patent No. 2169, Dated Sept. 12, 1865

Design for an Ox Yoke

The schedule referred to in these Letters Patent and making part of the same.

To all whom it may concern:

Be it known that I, W. T. Remington of Bridgeport, in the County of Fairfield and State of Connecticut have invented a new and ornamental Design for Ox Yoke; and I do hereby declare that the following is a full, clear and exact description of the same, reference being had to the accompanying drawings forming part of this specification, in which.

Figure 1, represents a sectional side elevation of this invention.

Figure 2, is a plan or top view of the same.

Similar letters of reference indicate corresponding parts.

This design refers to an ox yoke which is provided with ribs extending along the upper and lower edges of its body. These ribs are united in the middle by a pillar and they terminate in curved leaves.

A represents an ox yoke the upper and lower edges of which are ornamented by ribs a, b. These ribs are united in the centre by pillars c, and they terminate in leaves d. These leaves curve down in a graceful sweep and their edges are curled up as shown.

Between the ribs a, b, pillars c, and leaves d, are cavities e, which give to the whole a light and economical appearance.

2

DES. 2169

What I claim as new and desire to secure by Letters Patent, is

The design for an ox yoke as shown and described,

The above specification of my invention signed by me this 1st day of July 1865.
